(57) **CLAIM**

The ornamental design for an insulator as shown and described.

DESCRIPTION

FIG. 1 is a first perspective view of a first embodiment of an insulator;

FIG. 2 is a second perspective view of the insulator of FIG. 1;

FIG. 3 is a front elevation view of the insulator of FIG. 1;

FIG. 4 is a rear elevation view of the insulator of FIG. 1;

FIG. 5 is a right side view of the insulator of FIG. 1;

FIG. 6 is a left side view of the insulator of FIG. 1;

FIG. 7 is a top plan view of the insulator of FIG. 1; and,

FIG. 8 is a bottom plan view of the insulator of FIG. 1.

The evenly broken lines (dash-dash lines) shown in the Figures are only for illustrative purposes to show visible environmental structure and form no part of the claimed invention.

The solid parallel break lines shown in various ones of the Figures are only for illustrative purposes to indicate that the appearance of any portion of the illustrated article between the solid parallel break lines form no part of the claimed invention.

The boundary lines (as opposed to the evenly broken lines) shown in various ones of the Figures in dash-dot-dash form do not exist in reality in the respective article embodying the design and are only for illustrative purposes to show bounds of the claimed design. It is understood that the claimed design extends to the boundary lines but does not include the boundary lines or the portion of the article therein and/or beyond the boundary lines.
